X-RAY APPARATUS

Irving Ringler, New York, N. Y.

Application April 8, 1944, Serial No. 530,163

10 Claims. (Cl. 250—95)

1

This invention relates to X-ray apparatus. The technician, who operates X-ray equipment to produce certain results therewith, must calculate or otherwise determine the proper maximum voltage to be impressed upon the X-ray bulb; some technicians use "rule of thumb" methods, methods which are essentially founded upon pure guesswork. Even where the technician has attempted to reach a determination by calculation, the factors upon which he has had to rely, in the past, have been mostly in the same category, that is, "rule of thumb." However, it has been determined, by experimentation, that a number of factors must be considered for the purpose of determining the proper voltage to be applied. As those factors vary, so will the voltage vary. It has been observed that the factors vary in certain relations to each other, as well as in relation to the voltage.

For instance, the voltage to be applied varies in relation to the part of the body which is to be X-rayed. The density of the part, and its position within the body, are determining factors. Thus, whether it is desired to X-ray the lungs, or to X-ray the ribs, the voltage required for proper exposure of the X-ray film will be different. Then, again, the current applied to the filament of the bulb, and the time of exposure, that is, the number of milli-ampere seconds, will determine the variation in voltage required. The current applied, and the time of application, will be varied by the technician as he observes the patient. When he observes that the patient is of the nervous type, the technician may determine to decrease the time of exposure. He may determine to increase the current, or to effect his compensation by adjusting the voltage.

Increase of the distance of the object to be X-rayed from the X-ray bulb will require increase of the applied voltage. It has been discovered that whether the person to be X-rayed is an adult or infant must be taken into account, and, in that connection if the subject is under the age of 12, whether the X-ray is to be of thoracic tissue or of a non-thoracic part. If the party is adult, that is, over the age of 12, it has been discovered that it seems to matter little whether the part to be X-rayed is thoracic or non-thoracic; a constant is involved.

A further factor controlling the requisite voltage resides in the thickness of the part itself.

Finally, exposure to X-rays may be performed under a plurality of techniques. In one technique, a screen, known as the "Potter-Bucky diaphragm," may be used. In such case, the

2

technique is commonly known by the term, "bucky." Another technique utilizes a normal screen, and may be designated as the "non-bucky" technique. The bucky requires a higher voltage because of greater absorption of energy. It has been found, however, that the voltage to be applied when the bucky is used does not differ from the voltage with the non-bucky technique by a constant differential. The variation in voltage for the bucky, all other factors being constant and considered, have been determined by experimentation.

It is an object of the invention to provide a device with which a technician may determine with facility, from such assumptions as he may make, and from such known factors or known relations of these factors, and those facts which the technician may determine from observation of a subject patient, the required unknown factor or factors for making a proper X-ray exposure.

It is an object of the invention to provide a device which functions as a slide rule, by which the determination of peak voltage for proper exposure by X-ray equipment will be facilitated from certain known or determined factors which vary or cause variation of such peak voltage according to observations previously made.

It is an object of the invention to provide apparatus in conjunction with X-ray equipment, by which the varying factors entering into the production of an X-ray may be related to each other in determining the unknown factors of X-ray equipment operation.

It is an object of the invention to provide X-ray equipment having an adjustable control for peak voltage applied to the X-ray bulb, by which the technician may automatically set the apparatus for the required voltage, by setting the device in accordance with certain known or selected factors.

It is an object of the invention to resolve the radiographic technique into factors such that they may be associated with and be applied in the operation of a slide rule.

It is an object of the invention to eliminate, to as great a degree as possible, the matter of arbitrariness in determining factors for X-ray work, and also to eliminate the usual trial and error methods followed in determining these factors. In this relation, it is well recognized that the determinations of the proper voltages for X-ray exposures is a matter related not only to saving time and costs from obtaining immediate and accurate exposures, but also to the safety of

the patient, in guarding against over-exposure, or damage from unnecessary repeated exposures.

Much of present day X-ray practice is "rule-of-thumb," and fails to give consideration to factors such as the physical properties of X-rays of varying wave lengths. Yet variation of the voltage impressed upon the X-ray tube causes change in the wave length of the X-ray emitted.

It is an object of the invention to provide apparatus for use in operating X-ray apparatus which will function to eliminate, to as great a degree as possible, the "rule-of-thumb" in determining the factors in such use, and to compensate, as much as possible, for the effects of variations of wave length of the X-rays as the voltage impressed upon the tube varies.

As the result of investigation and observation, it has been determined that the factor for converting from the voltage necessary for exposure with the non-bucky technique to that with a Potter-Bucky diaphragm is not a constant, as has been the usually accepted theory. It has been determined that the conversion factor varies directly with the kilovolts impressed on the plate of the X-ray tube.

It is an object of the invention to provide a method of determining the peak voltage to be applied to an X-ray tube by which compensation is made automatically for differential differences between required voltages for non-bucky technique or bucky operation.

The determinations herein are discussed with relation to the voltage, or peak voltage, applied to the X-ray tube, in order to obtain the desired radiation for a proper exposure. Thus, two of the scales discussed are considered in terms of voltage.

However, it is apparent that the scales could be graduated in terms of wave length, absorption coefficients, the "R" unit, or some similar physical measurement in place of the kilovolts peak, or k. v. p., considered herein, without varying from the principle of the invention.

It is an object of the invention to provide means by which substantially all factors, or combinations of factors, governing proper X-ray exposure, will be considered in computation, and wherein all such factors enter quickly and accurately into such computations.

Other objects of this invention will be set forth hereinafter, or will be apparent from the description and the drawings, in which are illustrated embodiments of apparatus for carrying out the invention.

The invention, however, is not intended to be restricted to any particular construction, or to any particular arrangement of parts, or to any particular application of any such construction or any such arrangement of parts, or to any specific method of operation, or to any of the various details thereof, even where specifically shown and described herein, as the same may be modified in various particulars, or may be applied in many varied relations, without departing from the spirit and scope of the claimed invention, practical constructions embodying certain details of the invention being illustrated and described, but only for the purpose of complying with the requirements of the statutes for disclosure of operative embodiments, and without attempting to disclose all of the various forms and modifications in which the invention might be embodied.

On the drawings, in which the same reference characters refer to the same parts throughout, and in which are disclosed such practical constructions:

Fig. 1 is a plain view of a slide rule embodying features of the invention;

Fig. 2 is a transverse cross-sectional view, on the line 2—2 of Fig. 1;

Fig. 3 is a diagram showing the method of calibrating X-ray apparatus against slide rule readings;

Fig. 4 is a diagram illustrating the rate of increase of voltage when the bucky is used as against non-bucky technique;

Fig. 5 is a diagram showing the relation between milli-ampere seconds and kilovoltage peak;

Fig. 6 is a diagrammatic view, illustrating the manner in which a slide rule of this type may be incorporated into X-ray apparatus, automatically to control the voltage delivered to the X-ray tube in accordance with slide rule determinations;

Fig. 7 is an enlargement of a portion of Fig. 6, illustrating the relation of the slide rule to the auto-transformer and automatic operation of the X-ray tube upon setting the slide rule; and

Fig. 8 is a transverse cross-sectional view, substantially centrally of the hairline carrier in Fig. 7, and through the slide rule and the panel associated therewith.

Slide rule 10 may consist of a base 12 of wood, plastic or similar material. The base may be built up or otherwise formed to provide a groove or depressed section 14 between a pair of raised platforms 16 and 18. A slide 20 may be mounted in and retained for sliding movement relative to platforms 16 and 18. The side walls 22 of slide 20 and the walls 24 of platforms 16 and 18 facing into groove 14 may be formed or otherwise constructed to provide interlocking grooves 26 and fins 28. The fins are received in the grooves so that slide 20 will be retained firmly in groove 14, as slide 20 is permitted sliding movement relatively to base 12.

Slide 20 is in turn formed substantially of material the same as base 12. In this case, slide 20 takes the form of a body portion 38 having a platform 32 formed or otherwise provided thereon and extending upwardly therefrom at one edge extremity thereof. At the other edge extremity, slide 20 is provided with a thin wall formation 34. Fins 28 are formed on the outer faces of platform 32 and wall 34.

Between platform 32 and wall 34 is a groove 36, in which a slide 38 may be retained for sliding movement relative to slide 20. Walls 40 of groove 36 and the side walls 42 of slide 38 may be formed with interlocking grooves 44 and fins 46 to retain slide 38 with relation to slide 20, and yet permit adjustment of slides 20 and 38 with relation to each other and to base 12.

A hairline carrier 48, of the usual type, may be provided to straddle base 12. Carrier 48, in the usual manner, may comprise a frame 50 having a pair of bent arms 52, the ends 54 of which are bent towards each other. The arms are to be engaged in grooves 56 provided in side walls 58 of base 12. Frame 50 may retain a glass piece 60 or the like in which a hairline 62 may be formed. This hairline will co-operate with scales 64, 66, 68, 70, 72, 74 and 76 in the usual manner of slide rule hairlines, and in accordance with the further description.

Scale 64 may be provided upon a face 78 which is the top-most portion of platform 16. Scale 64 is graduated in terms of the factor of density of the part to be X-rayed. Any arbitrary dimension may be assumed for graduation of the scale in accordance with this factor, or the dimension may be determined in accordance with a dimension assumed for any one of the other scales. In

the instance illustrated, the dimension of graduations 80, shown demarcated on face 78, was arrived at by pasting on face 78 a piece of graph paper having ten divisions per inch. A zero point was adopted at line 82, and was marked with the symbol, "SK—N." Then each box on either side of this zero line was taken to indicate ten units, and was so indicated by notations 84 to indicate the relation of the particular graduations to different parts of the body. Scale 64 thus is one scale, but in terms of two markings, that is, the "Part" of the body, and the "Density" of that part to be X-rayed.

Scale 64 includes substantially all anatomical parts. The particular graduations depicted comprise eighty units or intervals, from +40 to -40. It has been determined in practice that the varying densities of the parts of the human body can be reduced, for radiographic purposes, to a simple set of coordinates. For purposes of illustration, the intervals on scale 64 have been denoted as follows:

- a. LU AP +38: Lung anterior posterior projection.
- b. LU LAT +24: Lung lateral projection.
- c. D SP LAT +20: Dorsal spine lateral projection.
- d. (RIB ST) (LSP LAT) +10: Ribs and sternum; lumbar spine lateral projection.
- e. (VISC) (D SP) (AP) +5: Visceral organs, gastro-intestinal tract; genito-urinary tract; gall bladder; bladder; liver; spleen.
- f. SK N: Skeletal; includes all extremities; pelvis; hips; antero-posterior projection of lumbar spine.
- g. No—SC-16: Nonscreen film; a special rapid fine grain film that is exposed in cardboard exposure holders and eliminates fluorescent screens.
- h. HO-34: This is the technique that is used with standard films in cardboard exposure holders.

On face 86 of platform 32 are the two scales 66 and 63, the milli-ampere seconds scale and the target distance scale, respectively. The graduation of these scales must now conform to the dimensions adopted either for scale 64, or whatever scale has had an arbitrary dimension adopted for it. For the purposes of clarity in continuing this description, it is assumed that the dimension for graduations 80 was the arbitrary assumption. Thus, scale 66, for the milliampere seconds, must conform to this dimensioning. This also must conform to the relationship which has been found to exist between the current-time factor and the peak voltage factor. Of course, a degree of arbitrariness can still be exercised in determining the proper dimensioning for graduations 88 of scale 66 since, in the final result, the variation can be taken up in graduation of scales 74 and 76. The same method may be followed in determining the dimensions of graduations 90 of scale 68.

It will be noted that scales 63 and 68 must be related to each other, since adjustment of scale 66, the milli-ampere seconds scale, with relation to scale 64, the density scale, immediately sets scale 68, the target distance scale, relatively to the voltage scales 74 and 76.

It will be noted that the indicia for graduations 88 are not in a regular progression as are graduations 80. This results from taking into account the relation between peak voltage and milli-ampere seconds, shown by the curve illustrated in Fig. 5. This curve was determined from a special

E. I. Photomicrograph in which kilovolts impressed on plate were plotted against milli-ampere seconds. For such a plot, substantially all other factors were maintained constant, while either voltage or current was varied. The relationship determined has been found to be constant for substantially all thicknesses of part.

The subject of scale 68, target distance, has been the subject of experimental determination, since Roentgen's inverse square law, while correct on basic concepts of physics, has its shortcomings in radiographic practice. For instance, the sensitivity curve of X-ray film limits the operation of this law. Furthermore, serious variations have been found to exist in the hard and soft ends of the X-ray spectrum, as they are applied in medical work. For instance, one set of determinations shows that the lower the voltage, the smaller the conversion factor as based upon an increase of distance. Likewise, it has been ascertained that either the harder rays or higher voltage will require higher voltage per unit of distance as the distance from target film to X-ray tube increases.

On face 92 of slide 38 are scales 70 and 72 which are concerned, respectively, with whether the patient is an adult or an infant, and, in the latter case, whether the part to be X-rayed is thoracic or non-thoracic, and with the thickness of the part to be X-rayed. Scale 70 is made necessary by a condition observed in practice. In the case of persons of 12 years or younger, a compensating factor must be introduced. This factor is found to vary not only in relation to the age of the patient, but also, in different fashion, by reason of whether the X-ray is to be made of matter which is thoracic or non-thoracic. It has been found that the peak voltage for proper X-ray exposure increases with increase of age when thoracic tissue is to be X-rayed. On the other hand, it has been found that the peak voltage for proper X-ray exposure decreases with increase of age when the part to be X-rayed is non-thoracic.

Scale 70 is graduated in such manner as to compensate for these variations in the types of matter, where the subject is of such age that the density of the matter has not as yet become uniform. If the slide rule were to be used only on subjects older than 12 years, scale 70 could be dispensed with. In such case, the single indication 94, marked "Adult," to which scale 70 is set when the patient is over 12 years old, would be all that would be necessary.

Scale 72 is graduated in terms of the actual thickness (in this instance, in centimeters) of the part to be X-rayed. It has been found that, contrary to conventional practice, kilovoltage peak is not a constant function of the thickness of a part without regard to changing photographic effects per centimeter change. For instance, in the lower kilovoltages, the change per centimeter has been found to be about two kilovolts, while in the higher voltages, the change per centimeter has been found to be three kilovolts. Thus, scale 72 is graduated in accordance with this variation in relationship, to compensate in the finally determined peak voltage.

On face 96 of platform 18 are scales 74 and 76. It will be noted that while substantially the same spacing of indications 98 is shown, there is variation in value of such spacing on the two scales, that is, the two scales do not vary at the same rate. The rate of variation in these two scales, which are the peak voltages for use with the

non-bucky technique or with the Potter-Bucky diaphragm, or, as it is commonly known, the "bucky," have been determined by experimentation and calculation. A graph, illustrating the variation in the increase of voltage for change from non-bucky technique to that in which the bucky is used, is illustrated in Fig. 4, where kilovoltage peak for non-bucky technique is plotted against the increase necessary where the bucky is utilized.

Aside from all of these determinations, which have been reached by experiment, it also has been determined that the readings of the meters of X-ray apparatus are so inaccurate that, when the slide rule is first used with any piece of X-ray apparatus, it is necessary to associate the slide rule with such X-ray apparatus by calibration. The slide rule itself is standardized against an X-ray machine which has been accurately calibrated. The modern high tension measurements have been found to be too inaccurate for the exact work required by such calibration. The different types of apparatus for the purpose of determining the voltage relations between two pieces of apparatus have been found to vary widely in performance and accuracy under varying climatic conditions, or to vary in efficiency. The end product of X-ray apparatus is the effect upon the X-ray film. For that reason, photometric calibration of the apparatus has been found most desirable.

For instance, a reading of voltages with an X-ray screen may be taken for exposures for certain parts of the body to obtain proper exposures. A number of these readings are plotted as a graph against the readings for voltage upon the slide rule for the same values of parts, milliampere seconds, and target distance. A graph for such purpose is shown in Fig. 3, where the calibration was effected for apparatus 100, to be described, where the slide rule had been incorporated into the control panel of X-ray apparatus.

In order that a more accurate factor may be used in place of maximum voltage, or kilovolts peak, or k. p. v., as it is usually abbreviated, a factor such as wave length, or the "R" units may be substituted for the indications. This, of course, would require some efficient indicating device for any of these units of graduation.

In the operation of the slide rule in conjunction with X-ray apparatus, the technician manipulates hairline 62, after he has set the different scales in accordance with determined factors or assumed factors, to read, on scales 74 and 76, the peak voltage required when the non-bucky technique or the bucky is used. For instance, if the technician knows that he is to X-ray the bone structure of the ribs, and not the tissue structure of the lungs, he will set hairline 62 at the position marked, "Ribs," on scale 64. Then he will move slide 20, in accordance with his predetermined purpose of a fast or slow exposure. This, of course, he would determine by observing the patient. If he observes that the patient would not remain quiet under long exposure, the technician knows that the number of milli-ampere seconds allotted must be low. The technician, therefore, determines for himself the time of exposure, and sets scale 66 with relation to scale 64 accordingly, of course using hairline 62 for accuracy. Now, scales 64 and 66 are related, and the technician now must determine what distance from the subject he will position the X-ray bulb. This, of course, will depend upon a number of factors known to the technician, and

observed by him in relation to the patient. This target distance is the distance of the X-ray tube from the film. Usually it may be read upon the scale on the apparatus, as the bulb is moved towards or away from the patient. When this distance is determined, carrier 48 is moved to bring line 62 into registry with that reading on scale 68.

The technician will have observed, of course 10 whether the patient is an adult or of or under the age of 12. In the event the patient is adult, indication 94 on scale 70 will be brought into registry with the hairline, and no further adjustments will be required in that connection. However, if the patient is under the age of 12, and, of course, the age will be known, slide 38 will be moved to bring the proper graduation on scale 70 into registry with the hairline. This, of course, would be determined by whether thoracic or non-thoracic matter were to be X-rayed.

Before the exposure will have been made, the particular part to be X-rayed would have been measured. After slide 38 has been adjusted as previously described, carrier 48 is now adjusted 25 to bring hairline 62 into registry with the proper graduation for thickness of part on scale 72. The technician now may read, either on scale 74 or scale 76, the proper peak voltage to which the apparatus will be set to make a proper X-ray exposure.

As shown in Fig. 6, this principle may be appropriated to X-ray apparatus 100 itself, which may include the usual elements of such X-ray apparatus. In this case, the slide rule is made a part of panel 102 upon which may be mounted certain of the parts of the apparatus. Mounted on or beneath that panel may be an auto-transformer 104 by which the voltage applied to the X-ray tube is controlled. The mains 105 from the electric power source are connected to this auto-transformer. One of the mains is also connected to a switch 107, that main also having the overload breaker 115 connected therein. This switch 45 is connected to a step-up transformer 109. The step-up transformer is connected to suitable rectifying means 111. From the rectifying means is derived the voltage for application to X-ray tube 113.

50 A plurality of taps 106 are taken off transformer 104, and are led to two sets of contacts 108 and 110. Such contacts are in separate lines spaced apart from each other. Each tap 106 may be led 55 to a contact 108 or a contact 110. In some cases, the same tap may be connected both to a contact 108 and to a contact 110. In such cases, the associated contacts 108 and 110 will not be at the same position transversely of panel 102 since they 60 are to effect variation in peak voltage for non-bucky or bucky, just as scales 74 and 76 compensate for these differences.

A base 112, similar to base 12, may have a scale 114 similar to scale 64 graduated on a face 116. 65 A slide 118 may be mounted with relation to base 112 in a manner similar to slide 20. Slide 118 may carry scales 120 and 122 disposed thereon in a manner similar to scales 66 and 68. Slide 118 may also carry slide 124, which may be graduated 70 with scales 126 and 128 similar to scales 70 and 72.

A carrier 130 having a hairline 132 may likewise be mounted upon base 112, for movement with relation to that base in adjusting line 132 with relation to the different graduations. Carrier 130 75 may comprise a body 134 having arms 136 engaged

in grooves 138 in the side faces 140 of base 112. Body 134 may have an opening 144 at which a glass 146 may be retained. Upon glass 146, hair-line 132 may be etched.

Body 134 may carry a contactor 156. This contactor may be carried at the end of an arm 157 projecting laterally from body 134 and may include a roller contact 158 held in engagement, by means of a spring, with a contact rail 160. Contact rail 160 is electrically connected to one side of switch 167. Furthermore, a second contactor 162 is provided to ride upon and along contacts 108 or contacts 110. Contactor 162 may comprise an arm 163 extending laterally from body 134 in a direction opposite the projection of arm 157. Carried and slidable upon arm 163 is a sleeve 165. A pin 167 extending from arm 163 into a slot 177 in sleeve 165 provides limits for movement of sleeve 165 with relation to arm 163. Electrical connection is effected between sleeve 165 and arm 163. An additional arm 169, substantially parallel to arm 163, bears indicia 171. A pointer 179, carried by sleeve 165, indicates the adjusted position, with relation to contacts 108 and 110, of a spring-pressed shoe 173 at the end of sleeve 165, that is, whether the adjustment is for bucky or non-bucky technique. To permit manipulation of the sleeve without danger to the technician, a knob 175 of non-conducting materials is affixed to sleeve 165. Electrical connection between contactors 158 and 162 is made by a conductor 181 which may be moulded or otherwise embedded or retained within body 134, or insulated to protect the technician. Thus, the technician, on adjusting the slides 118 and 124 with relation to the base, and sleeve 165 with relation to arm 163, automatically would determine the voltage to be applied to the bulb.

Many other changes could be effected in the particular apparatus designed, and in the method of operation set forth, and in specific details thereof, without substantially departing from the invention defined in the claims, the specific description being merely of operative embodiments capable of illustrating certain principles of the invention.

What is claimed as new and useful is:

1. A calculating device for use in controlling the operation of X-ray apparatus, comprising a pair of spaced apart, fixedly related scale-carrying members, one of the members carrying a scale graduated in terms of the densities of the parts to be X-rayed, the other member carrying a scale graduated in terms of X-ray radiation necessary, and a plurality of members movable between the two relatively fixed members, one movable member being contiguous to the fixed member carrying the scale of density of the part, said one movable member carrying a scale calibrated in terms of the product of the time of exposure and the current necessary for heating the filament of the X-ray tube and another scale calibrated in terms of the distance of the part to be X-rayed to the X-ray tube of the X-ray apparatus, and the other movable member carrying a scale graduated in terms of the thickness of the part to be X-rayed, said one movable member being adjusted to associate a selected graduation of said product of time and current necessary for filament heating with the graduation for density of the part to be X-rayed, said other movable member being adjusted between the said one movable member and the scale of X-ray radiation to associate a scale graduation on the

other movable member with the scale on said one movable member for a distance between part and X-ray tube to determine from the resultant association of the graduation for the thickness of the part to be X-rayed with a graduation on the scale of X-ray radiation the X-ray radiation necessary to effect an X-ray for the part involved.

2. A calculating device for use in controlling the operation of X-ray apparatus, comprising a pair of spaced apart, fixedly related scale-carrying members, one of the members carrying a scale graduated in terms of the densities of the parts to be X-rayed, the other member carrying a scale graduated in terms of X-ray radiation necessary, and a plurality of members movable between the two relatively fixed members, one movable member being contiguous to the fixed member carrying the scale of density of the part, said one movable member carrying one scale calibrated in terms of the product of the time of exposure and the current necessary for heating the filament of the X-ray tube and another scale calibrated in terms of the distance of the part to be X-rayed to the X-ray tube of the X-ray apparatus, and the other movable member carrying a scale graduated in terms of the thickness of the part to be X-rayed, and a scale calibrated in terms of the age of the individual to be X-rayed on the basis of whether the part to be X-rayed is thoracic or non-thoracic, said one movable member being adjusted to associate a selected graduation of said product of time and current necessary for filament heating with the graduation for density of the part to be X-rayed,
3. A calculating device for use in controlling the operation of X-ray apparatus, comprising a pair of spaced apart, fixedly related scale-carrying members, one of the members carrying a scale graduated in terms of the densities of the parts to be X-rayed, the other member carrying a scale graduated in terms of X-ray radiation necessary when a normal screen is used and the other in terms of variations in the X-ray radiation necessary when a Bucky screen is used, and a plurality of members movable between the two relatively fixed members, one movable member being contiguous to the fixed member carrying the scale of density of the part, said one movable member carrying one scale calibrated in terms of the product of the time of exposure and the current necessary for heating the filament of the X-ray tube and another scale calibrated in terms of the distance from the part to be X-rayed to the X-ray tube of the X-ray apparatus, and the other movable member carrying a scale graduated in terms of the thickness of the part to be X-rayed and another scale calibrated in terms of the age of the individual to be X-rayed on the basis of whether the part to be X-rayed is thoracic or non-thoracic, said one movable member being adjusted to associate a selected graduation of said product of time of exposure and the current necessary for filament heating with the graduation for density of the part to be X-rayed, said other movable member being ad-

justed to associate the graduation for the age of the individual to be X-rayed with the scale on said one movable member for the distance between part and X-ray tube to determine from the resultant association of the graduation for the thickness of the part to be X-rayed with a graduation on the scales of X-ray radiation the X-ray radiation necessary to effect an X-ray for the part involved.

4. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means for producing calibratedly varied potentials at its various positions in relation to the scale of the scale-carrying member, and a plurality of members movable between the scale-carrying and circuit members, one movable member being contiguous to the circuit member, said one movable member having a scale calibrated to superimpose on the fixed relationship between the scale-carrying and circuit members for each graduation on the fixed scale-carrying member a factor in terms of the thickness of the part to be X-rayed, the movable members also providing means for superimposing upon said fixed relationship a factor in terms of the distance between the object to be X-rayed and the X-ray tube, to determine from the resultant association of factors on the movable members with said fixed relationship the potential necessary to produce the radiation required for the X-ray of the part involved.

5. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means for producing calibratedly varied potentials at its various positions in relation to the scale of the scale-carrying member, and a plurality of members movable between the scale-carrying and circuit members, one movable member being contiguous to the scale-carrying member, said one movable member having a scale thereon calibrated to impose on the fixed relationship between the scale-carrying and circuit members for each graduation on the fixed scale-carrying member a factor in terms of the product of the time of exposure and the current necessary for heating the filament of the X-ray tube, the other movable member having a scale graduated in terms of the thickness of the part to be X-rayed and being located in juxtaposition to and being adjustable to locate its scale with relation to the circuit member, the movable members also providing means for superimposing upon said fixed relationship a factor in terms of the distance between the object to be X-rayed and the X-ray tube, to determine from the resultant association of factors on the movable members with said fixed

relationship the potential necessary to produce the radiation required for the X-ray of the part involved.

6. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means for producing calibratedly varied potentials at its various positions in relation to the scale of the scale-carrying member, and a plurality of members movable between the scale-carrying and circuit members, one movable member being contiguous to the scale-carrying member, said one movable member carrying scales one of which is calibrated in terms of the product of the time of exposure and the current necessary for heating the filament of the X-ray tube, the other movable member having scales one of which is graduated in terms of the thickness of the part to be X-rayed, said other movable member being located in juxtaposition to and being adjustable to locate its said scale with relation to the circuit member, to determine from the resultant association of factors on the movable members with said fixed relationship the potential necessary to produce the radiation required for the X-ray of the part involved.

7. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means for producing calibratedly varied potentials at its various positions in relation to the scale of the scale-carrying member, and a plurality of members movable between the scale-carrying and circuit members, one movable member being contiguous to the scale-carrying member, said one movable member carrying scales one of which is calibrated in terms of the product of the time of exposure and the current necessary for heating the filament of the X-ray tube, the other movable member having scales one of which is graduated in terms of the thickness of the part to be X-rayed, and the other of which is calibrated in terms of the age of the individual to be X-rayed on the basis of whether the part to be X-rayed is thoracic or non-thoracic, said other movable member being located in juxtaposition to and being adjustable to locate its said scales with relation to said one movable member and said circuit member to determine from the resultant association of said other movable member with the circuit member the potential necessary to produce the radiation required for the X-ray of the part involved.

8. X-ray apparatus including an X-ray tube, and means for supplying an electrical potential to the X-ray tube, the supplying means including a circuit member, and means for controlling the member for imposing on the X-ray tube the

proper potential for the production of the required X-ray radiation; said controlling means including a scale-carrying member substantially fixedly related to the circuit member, the scale-carrying member including a scale graduated in terms of the densities of the parts to be X-rayed, the circuit member having means disposed in relation to the scale of the scale-carrying member for producing calibrately varied potentials at its various positions in relation to whether a normal screen is used or a Bucky screen is used, and a plurality of members movable between the scale-carrying and circuit members, one movable member being contiguous to the scale-carrying member, said one movable member carrying scales one of which is calibrated in terms of the product of the time of exposure and the current necessary for heating the filament of the X-ray tube, the other movable member having scales one of which is graduated in terms of the thickness of the part to be X-rayed, and the other of which is calibrated in terms of the age of the individual to be X-rayed on the basis of whether the part to be X-rayed is thoracic or non-thoracic, said other movable member being located in juxtaposition to and being adjustable to locate its said scales with relation to said one movable member and said circuit member to determine from the resultant association of said other movable member with the circuit member the potential necessary to produce the radiation required for the X-ray of the part involved.

9. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means disposed in relation to the scale of the scale-carrying member for producing calibrately varied potentials at its various positions in relation to whether a normal screen is used or a Bucky screen is used, a plurality of members movable between the scale-carrying and circuit members, one movable member being contiguous to the scale-carrying member, said one movable member carrying scales one of which is calibrated in terms of the product of the time of exposure and the current necessary for heating the filament of the X-ray tube, the other movable member having scales one of which is graduated in terms of the thickness of the part to be X-rayed, and the other of which is calibrated in terms of the age of the individual to be X-rayed on the basis of whether the part to be X-rayed is thoracic or non-thoracic, said other movable member being located in juxtaposition to and being adjustable to locate its said scales with relation to said one movable member and said circuit member, and a member movable with relation to the fixedly related scale-carrying and circuit members and the movable scale-carrying members for determining the effective potential for the circuit member in accordance with the position to which said other movable member is adjusted with relation to said one movable member.

10. X-ray apparatus including an X-ray tube, and means for supplying an electrical potential to the X-ray tube, the supplying means including a circuit member, and means for controlling the member for imposing on the X-ray tube the proper potential for the production of the required X-ray radiation; said controlling means including a scale-carrying member substantially fixedly related to the circuit member, the scale-carrying member including a scale graduated in terms of the densities of the parts to be X-rayed, the circuit member having means disposed in relation to the scale of the scale-carrying member for producing calibrately varied potentials at its various positions, a plurality of members movable between the scale-carrying and circuit members, one movable member being contiguous to the scale-carrying member, said one movable member carrying scales one of which is calibrated in terms of the product of the time of exposure and the current necessary for heating the filament of the X-ray tube and the other of which is graduated in terms of the distance from the object to be X-rayed to the X-ray tube, said one movable member being movable to position a graduation of one of its scales in relation to one of the graduations of the scale of density of part, the other movable member having thereon scales one of which is graduated in terms of the thickness of the part to be X-rayed, said other movable member being adjustable between said one movable member and the circuit member to position one of the scales on said other movable member with relation to the adjusted scales of said one movable member and thereby to determine the potential necessary to produce the radiation required for the X-ray of the part involved.

IRVING RINGLER.

Certificate of Correction

Patent No. 2,455,522.

December 7, 1948.

IRVING RINGLER

It is hereby certified that errors appear in the printed specification of the above numbered patent requiring correction as follows:

Column 5, line 34, for "SK N:" read *SK N O:*; line 37, for "No—SC—16" read *No—SC—16*; line 41, for "HO—34" read *HO —34*; and that the said Letters Patent should be read with these corrections therein that the same may conform to the record of the case in the Patent Office.

Signed and sealed this 24th day of May, A. D. 1949.
